UNITED STATES PATENT OFFICE.

JORGEN JORGENSEN, OF SOUTH OMAHA, NEBRASKA.

ALFALFA-CUTTER.

943,308.

Specification of Letters Patent. Patented Dec. 14, 1909.

Application filed December 2, 1903. Serial No. 405,727.

To all whom it may concern:

Be it known that I, JORGEN JORGENSEN, a citizen of the United States, and a resident of South Omaha, in the county of Douglas and State of Nebraska, have invented certain new and useful Improvements in Alfalfa-Cutters, of which the following is a specification.

My invention relates to the general class of vegetable cutters and crushers, and more particularly to machines for cutting alfalfa and similar materials for use as animal food.

It is the object of my invention to provide a machine of this class by which all materials which pass through the machine must be reduced to particles small enough to pass through a certain screen arranged therein.

My invention relates more particularly to the construction and arrangement of the cutting-cylinder and ledger-blades and the combination therewith of a screen through which the cut material must pass before escaping from the cutting mechanism.

A machine embodying my invention is shown in the accompanying drawings in which—

Figure 1 is a longitudinal section thereof, the central part of the feed-table and frame being broken away and the rearward portion of the frame being shown in elevation only, Fig. 2 is a front elevation with the cover or easing over the feed- and cutting-cylinders removed, Fig. 3 is a side elevation of the head portion of the machine, Fig. 4 is a detail section taken through the axis of the cutting-cylinder and on the plane indicated by the line $a-a$ of Fig. 5, Fig. 5 is a detail transverse section of the cutting-cylinder and ledger-blade bar, and Fig. 6 is a detail section through the teeth of a pair of the knife-plates, the section being on the plane indicated by the line $y-y$ of Fig. 3.

In the construction of the machine shown I provide a frame 1, at the front end of which are carried the driving mechanism and the feed- and cutting-cylinders. The central and rearward portions of the frame support a feed-table 2 which is provided with side-boards 3, as indicated. A number of chains 4 are passed over the feed-table, said chains being provided at intervals with teeth 7 and passing over sprockets carried on transverse shafts 5 and 6, arranged, respectively, at the front and rear ends of the

table. The chains, preferably, lie in grooves in the top of the table and the teeth 7 extend above the same to engage materials lying thereon and carry the same toward the cutting mechanism at the head of the machine.

The cutting and feed mechanism is driven from the cutting-cylinder shaft 8 which is journaled in suitable bearings arranged in the metal side-frames 10 which are arranged on the frame 1 near the front end thereof, as shown. The said shaft 8 carries at its outer ends pulleys 9, either or both of which may be connected by belts with a suitable source of power. In the frames 10 is a transverse stationary shaft 11 on one end of which is rotatably mounted a gear 12 which meshes with a pinion secured on the shaft 8. A pinion 13 is connected with the gear 12 alongside the same and said pinion meshes with a gear 14 secured on the transverse shaft 15. On the opposite end of the shaft 15 is a pinion 16 which meshes with a gear 17, rotatably mounted on the shaft 11. Sprockets 18 and 19 are secured to the gear 17 alongside the same as indicated in Fig. 2. From the sprocket 18 a chain 20 extends to a sprocket 21 carried on the end of the feed-cylinder shaft 22. From the sprocket 19 a chain 23 extends to a sprocket 24 rotatably mounted on a stud arranged on the side of the frame 1. Said sprocket 24 has connected thereto a gear 25 which engages a gear carried on the end of the feed-table shaft 5. By means of the aforesaid driving connections the cutting-cylinder is driven at a relatively high speed, while the feed-cylinder and the chains over the feed-table are driven at a relatively low speed, all in the directions indicated by arrows in Figs. 1 and 3.

The feed-cylinder is arranged above the forward end of the feed-table 2 and comprises a drum 26 mounted on the shaft 32 and provided on its periphery with pointed teeth 27. To permit a certain raising and lowering of the cylinder, relative to the feed-table, the ends of the shaft 22 are extended through slots 28 in the side-frames 10 and are journaled in bearings formed in the radius bars 29, the forward ends of said bars being pivoted on the shaft 11 and the slots 28 being concentric to said shaft. By means of the radius bars a uniform distance is maintained between the centers of the sprockets 18 and 21, so that the chain 20 is kept at a

uniform tension and the raising and lowering of the cylinder will not interfere with the driving thereof. At the rearward ends of the radius bars 29 a cross-bar 30 is connected therewith, the said cross-bar extending through slots in the frames 10 and, between the said frames, carrying the shoe-plate 31. The connections between the ends of the cross-bar and the radius bars are made by means of bolts passing through slots in the upturned ends of the cross-bar, so that a slight adjustment may be made thereby to change the relation of the cross-bar and shoe-plate to the feed-cylinder.

The cutting-cylinder is made up of a series of knife-plates 32 mounted between end-plates 33 and on a tube 34 which passes over the shaft 8. Adjoining one of the end-plates 33 a wheel 35 is secured to the shaft, as shown in Fig. 4. On the said end-plate and wheel are peripheral flanges which are connected by means of a break-pin 36. The said pin is the sole driving connection between the shaft 8 and the cylinder and is so proportioned that it will be sheared off and the connection broken should the cylinder be subjected to any undue stress, as, for example, should materials be fed thereinto too rapidly or some hard foreign body be contained in the material. The knife-plates 32 consist of circular plates which are provided on their peripheries with teeth, the form of which is best shown in Figs. 4, 5 and 6. The plates are arranged in pairs, the adjoining sides of each pair of plates being perfectly flat and fitting together, while the outer faces of the teeth of each pair of plates are beveled so that V-shaped spaces are left between the teeth of each adjoining pair of plates. The front faces of the teeth are given a slight forward rake or inclination both longitudinally and circumferentially of the cylinder, and the backs of the teeth, when viewed from the end of the cylinder, are of substantially spiral form. The plates are secured to each other and to the end-plates 33 by bolts 37 which pass through holes 38 in the plates, said holes being arranged in a circle concentric to the shaft. The number of said holes 38 is made three or more times that of the bolts and in each plate the holes are made the same with reference to the front edges of the teeth. Thus, by passing the bolts through different sets of the holes in the adjoining pairs of plates, the front edges of the teeth on the adjoining pairs of plates may be brought into a staggered or non-aligned relation to each other longitudinally of the cylinder. Above the cutting-cylinder a cross-bar 39 is secured between the frames 10 and on said bar the ledger-blades 40 are adjustably secured by bolts passing through slots therein. The ends of said ledger-blades are V-shaped and extend between the

teeth of the cutting-cylinder, the edges thereof being brought to a shearing relation with the edges of the cylinder teeth. The cylinder teeth may be sharpened by removing the knife-plates from the cylinder and grinding the front faces of the teeth. The ledger-blades may be sharpened by grinding the end-faces thereof, the material removed by grinding being compensated by adjusting the bodies of the blades in closer to the cylinder.

From the cross-bar 39 a perforate casing or screen 41 extends around the cylinder to the front end of the feed-table which terminates in a plate 42 having V-shaped teeth on the front edge thereof which extend in between the cylinder teeth similarly to the ledger-blades but not close enough to be in a shearing relation to said teeth. Extending downwardly from the screen 41 is a hopper 43 adapted to receive the materials which pass through the screen. A removable casing or cover 44 is disposed over the cylinders, following the outline of and being connected with the side-frames 10, as shown.

The operation of the machine will be apparent from the foregoing. Materials placed on the feed-table are carried forward by the toothed chains 4, being directed by the shoe-plate 31 so as to pass below the feed-cylinder, the teeth of which engage the material and force it into engagement with the cutting-cylinder teeth. Loose materials in passing below the feed-cylinder are compressed more or less thereby, but, should the material under the cylinder at any time exert a sufficient upward pressure thereon, the cylinder will be lifted thereby, swinging on the radius bars 29, as described. The shoe-plate 31, also being connected with the radius bars, will swing upward with the cylinder so as to remain in the same position relative thereto. The material when engaged by the raking or hook-like teeth of the cylinder will be carried thereby into engagement with the ledger-blades 40 and cut in passing through the same. A portion of the material remaining in engagement with each of the cylinder teeth, the same will be carried thereby into the chamber between the cylinder and the screen 41, where such of the material as has been cut to particles small enough to pass through the screen will escape through the same and into the hopper 43. The uncut portions of the material will continue to be carried around by the cylinder until all are reduced to particles small enough to escape through the screen.

Now, having described my invention, what I claim and desire to secure by Letters Patent is:

1. In a machine of the class described, in combination, cutting devices comprising a

- toothed cylinder and ledger-blades arranged in shearing relation thereto, a feed-table, means for actuating materials over said table toward the cutting devices, a toothed feed-cylinder arranged over the feed-table adjacent to the cutting devices, flexible driving means for said feed-cylinder arranged to permit a raising and lowering thereof relative to the feed-table, a shoe-plate arranged adjacent to the feed-cylinder for directing materials thereunder, and means connecting the shoe-plate and cylinder whereby when the cylinder is raised the shoe-plate will be maintained in the same position relative to the cylinder.
2. In a machine of the class described, the combination with feeding devices of a cutting cylinder consisting of a series of plates each having teeth formed on the periphery thereof, the plates being arranged in pairs, the teeth of each pair of plates coinciding in position longitudinally of the cylinder and forming in effect single teeth having concave front faces and inclined cutting edges, the teeth of the different pairs of plates being in non-alined positions longitudinally of the cylinder, and ledger-blades of a form adapting each of the same to extend between the teeth of adjoining pairs of the plates and in shearing relation to the cutting edges of said teeth, each of said ledger-blades being independently adjust-
able in a direction substantially radial to the cylinder.
3. In a machine of the class described, a cutting-cylinder consisting of a series of plates each having on the periphery thereof a plurality of raking or overhanging teeth with inclined cutting edges, the plates being arranged in pairs, the teeth of each pair of plates coinciding in position longitudinally of the cylinder, each of the plates having a series of holes formed therein and in constant relation to the cutting edges of the teeth, and connecting bolts passing longitudinally of the cylinder through some of the holes in each of the plates.
4. In a machine of the class described, a cutting cylinder consisting of a series of knife-plates, end-plates, and bolts passing longitudinally of the cylinder through said end-plates and knife-plates, a wheel secured to the cylinder shaft adjoining one of said end-plates, and a break-pin connecting said wheel and end-plate for the purpose set forth.

In testimony whereof I have hereunto subscribed my name in the presence of two witnesses.

JORGEN JORGENSEN.
